United States Patent Office.

JOHN W. LATCHER OF ALBANY, AND JOHN YOUNG, OF AMSTERDAM,
ASSIGNORS TO JOHN YOUNG, OF AMSTERDAM, NEW YORK.

Letters Patent No. 61,012, dated January 8, 1867.

IMPROVED WRINGING-MACHINE.

The Schedule referred to in these Letters Patent and making part of the same.

TO ALL WHOM IT MAY CONCERN:

Be it known that we, JOHN W. LATCHER, of Albany, in the county of Albany, and State of New York, and JOHN YOUNG, of Amsterdam, in the county of Montgomery, and State aforesaid, have invented a new and useful Improvement in Wringing-Machines; and we do hereby declare that the following is a full, clear, and exact description of the construction and operation of the same, reference being had to the annexed drawings, making a part of this specification, in which—

Figure 1 is a vertical sectional view of a wringing-machine, exhibiting axial views of the gears having conical holes formed through them to receive the shafts; and

Figure 2 is a side view of the variable bearing for the journals of the conical gears.

The object of this invention is to form and control gears applied on shafts of clothes-wringers so as to admit of the elevation and depression of the upper roller or rollers from and to the lower one by having the holes through the gears made conical and large enough at the contracted end to receive the shaft; a slot also is formed in the contracted end of the gear to stride a pin driven into the shaft at the proper place, near the standards of the wringer. An annular rim or thimble is also formed on the gear at the enlarged end, which answers the purpose of a journal, and which turns in an adjustable or variable bearing, the two bearings to said gears being in one fixed position with relation to each other, but having a vertical movement with relation to the lower shaft and other framework. Thus it will be seen that each gear has an eccentric as well as a concentric motion with relation to its own shaft.

A, fig. 1, represents the frame of a wringing-machine; B B' the roller shafts. The shaft B' is the driving-shaft, having a crank *c* secured thereto. D exhibits a vertical central section of the bracket which serves as a vertical guide for the movement of the adjustable variable bearing plate E, (also shown in fig. 2, side view,) which keeps the conical-bored wheels F F always in mesh, notwithstanding the elevation or depression of the shafts B B' carrying with them the contracted end of said gears. When the shafts B B' are compressed or touch each other the positions of their axis of motion will be reversed, as is obvious by reference to the drawing, fig. 1. A slot, *g*, is formed in the contracted end of the gear to stride a pin, *h*, driven into the shaft so that the gears and shafts shall rotate correspondingly. The annular rim or thimble *i*, which answers the purpose of a journal to the gears, is fitted to turn in suitable bearings in the adjustable variable bearing plate E. A slight packing or cushion of India rubber, or other suitable material, is interposed between the plate E and the bracket D, as represented at *b*, to prevent noise, &c., and also to equalize the gears on their shafts. A spring, *l*, may be used, as is shown at the rear end of the upper shaft, in order that the roller may not be elevated to an unequal height.

What we claim as our invention, and desire to secure by Letters Patent, is—

1. We claim the employment or use of conically-bored wheels F F, applied to shafts of clothes-wringers, for the purpose shown and described.
2. We claim, in combination with the gears F F, the variable bearing plate E, all constructed and arranged to operate substantially as set forth.
3. We claim, in combination with the wheels F F and bearing plate E, the elastic cushion *k*, for the purposes set forth.
4. We claim, in combination with the conically-bored gear-wheels F F, plate E, and cushion *k*, the relay spring *l*, for the purpose described.

J. W. LATCHER,
JOHN YOUNG.
